DESIGN FOR A COMBINED TABLE, SINK,
STOVE, AND CABINET UNIT FOR VE-
HICLE TRAILERDonald F. Ham, Chicago, Ill., assignor to Chicago
Streamlite Corporation, Chicago, Ill., a corporation of Illinois

Application December 3, 1947, Serial No. 142,928

Term of patent 3½ years

(Cl. D14—3)

To all whom it may concern:

Be it known that I, Donald F. Ham, a citizen of the United States, residing at Chicago, in the county of Cook and State of Illinois, have invented a new, original, and ornamental Design for Combined Table, Sink, Stove, and Cabinet Unit for Vehicle Trailer, of which the following is a specification, reference being had to the accompanying drawing, forming a part thereof.

The rear surface of the side including the stove unit and the back of the entire unit are substantially plain.

The dotted line disclosure of a trailer body outline is for illustrative purpose only.

The figure shows a perspective view of a table, sink, stove and cabinet unit for vehicle trailer embodying the invention.

I claim:

The ornamental design for combined table, sink, stove, and cabinet unit for vehicle trailer, substantially as shown and described.

DONALD F. HAM.
